(57) **CLAIM**

We claim the ornamental design for a magnet educational nutrition chart, as shown and described.

DESCRIPTION

FIG. 1 is a perspective view of the design of the present invention for a magnet educational nutrition chart;

FIG. 2 is a front side elevation view thereof;

FIG. 3 is a rear side elevation view thereof;

FIG. 4 is a right side elevation view with the left side view elevation being a mirror image thereof;

FIG. 5 is a top plan elevation view thereof; and,

FIG. 6 is a bottom plan view thereof.

In the drawings, the broken line showing depicts environmental subject matter and forms no part of the claim.
